(57) **CLAIM**

I claim the ornamental design for a postal carrier mail bag, as shown and described.

DESCRIPTION

FIG. 1 is a front, side and top perspective view of the postal carrier mail bag, showing the top flap open;

FIG. 2 is a side elevation view of the postal carrier mail bag;

FIG. 3 is a side elevation view of the opposite side of the postal carrier mail bag;

FIG. 4 is a rear view of the postal carrier mail bag;

FIG. 5 is a front view of the postal carrier mail bag;

FIG. 6 is a bottom view of the postal carrier mail bag;

FIG. 7 is a top plan view of the postal carrier mail bag, showing the top flap closed; and,

FIG. 8 is a top plan view of the postal carrier mail bag, showing the top flap open.

The broken lines representing stitching are part of the claimed design.
